Int. Cl. D8—08

U.S. Cl. D8—233

FIG. 1 is a side elevational view of a radial arm milk hose support showing my new design;

FIG. 2 is a front elevational view;

FIG. 3 is an elevational view taken from the side opposite that shown in FIG. 1;

FIG. 4 is a top plan view; and

FIG. 5 is a bottom plan view.

The support arm has been shown as broken away in FIGS. 1, 2 and 3 to indicate indeterminate length.

We claim:

The ornamental design for a radial arm milk hose support, as shown and described.
